12 Claims. (Cl. 336—149)

This invention relates to adjustable transformers of the type having a high resistance brush slideable along a circular, electrical contact surface on the exterior of the winding, usually connected as an autotransformer, and more in particular to improved means for dissipating the heat generated in the area where the brush touches the winding contact surface.

In sliding brush autotransformers a large amount of heat is generated at the interface where the brush touches the contact surface of the winding. This causes the interface to be the hottest spot in the autotransformer, since the temperature in the area of contact is many times that of the remaining portions of the autotransformer. The result is that the temperature at the interface is the limiting factor in the construction and operation of sliding brush autotransformers because the high temperature will cause insulation to fail, or the winding contact surface to burn out or become deformed before other parts of the autotransformer are damaged.

The core of a sliding brush autotransformer operates at a much lower temperature than the winding-brush interface. Consequently, the core is theoretically capable of acting as a heat sink to remove heat from the high temperature interface. However, the core is prevented from being an efficient heat sink by the manner in which sliding brush autotransformers are conventionally made. The winding of such autotransformers is a toroidal coil wound on an annular core. The winding must be raised near the outer circumference of the core to furnish a surface that can be machined flat to form the contact surface that the brush slides over. The winding is usually raised by placing on the core a plastic form member having a flat, thickened outer circumference, and an insulated wire conductor is coiled around the form member. This causes the thickened portion of the form member to be interposed between the winding contact surface and the core. Thus the winding and core are separated by a good thermal insulating barrier in the area where the greatest amount of heat is generated, and the core cannot function efficiently as a heat sink for the high temperature interface.

The limiting effect of the high temperature interface is that sliding brush autotransformers must be operated at a much lower load current level than would be permissible for the remaining materials and elements employed. This results in the size, weight, and cost of the apparatus being increased above that which would be necessary for the thermal and electrical conditions encountered in other parts thereof. Another drawback is that the limiting effect of the high temperature interface prevents the use of higher classes of insulation; the reason is that the winding-brush interface will fail because of the high temperature encountered there before the remaining portions of the apparatus will be raised to temperatures high enough to cause an electrical insulation failure.

It has long been known in the prior art that the above problems could be solved if efficient means could be devised for dissipating the heat generated at the interface between the brush and winding. Numerous solutions have been proposed with this end in mind. For example, fans or blowers have been employed to cool autotransformers; thermal conductors have been placed in the brush to carry heat therefrom; and the heat absorbing capacity of

2

the core has been improved. Another prior art arrangement for increasing the heat dissipated at the brush surface is to place brush-engaged contacts at a location remote from the windings and core. The above expedients suffer from the disadvantages that either they are ineffective in reducing the temperature at the brush interface an amount sufficient to eliminate the problem, or else they result in an increase in the cost, size, and weight of the apparatus that outweighs any increase in heat dissipation sufficiently to render the expedient impractical for commercial embodiments of the apparatus.

Our invention is based on the realization that the means for removing heat from the high temperature interface need not necessarily dissipate heat directly to the atmosphere. Instead, the heat removing means need merely absorb heat from the hot-spot area adjacent the interface and carry the heat to other lower temperature areas of the autotransformer. This results in more uniform temperature distribution throughout the autotransformer, and enables an autotransformer core and winding assembly to use higher temperature insulation and to be operated at greater load capacities for a given size.

We accomplish the above desirable results by employing a heat sink beneath the winding in the area adjacent the winding contact surface. A related heat sink arrangement requiring a split tube has been proposed in United States Letters Patent 2,463,105. However, the arrangement taught by that patent suffers from the disadvantages that the split tube surrounding the core increases the size and cost of the apparatus beyond practical commercial limitations, and the heat absorbing capacity of the heat sink is not uniform for all brush positions in that the area of the tube usable for effectively conducting heat is greatly reduced when the brush is at either end of the winding. Another disadvantage is that the orientation of the tube with relation to the flux in the core requires the tube to be split throughout its length so that it will not be a short-circuited turn.

Accordingly, one object of our invention is to provide an improved heat sink for dissipating heat generated at the high temperature interface between an autotransformer brush and winding so as to solve problems previously encountered by the prior art without incurring the disadvantages of prior art heat sinks.

A more general object of the invention is to provide an improved sliding brush autotransformer operable at higher load levels for any given size and weight of its core and winding assembly.

Another object is to improve adjustable autotransformer construction so that the use of relatively high temperature insulation is practical.

Another object is to provide sliding brush autotransformers with a heat sink that prevents burn-out or deformation of the winding contact surface at relatively high load levels.

A further object of the invention is to provide an adjustable sliding brush autotransformer with a heat sink that has the same heat absorbing effect for all locations of the brush on the winding contact surface.

Another object is to provide adjustable autotransformers with a heat sink that is an integral metal body having continuous outer surfaces, yet is not a short-circuited turn about the autotransformer core.

A further object is to provide a heat sink arrangement for sliding brush autotransformers that eliminates the winding brush interface temperature as the limiting factor in the construction and operation of the autotransformer.

A further object is to provide a heat sink in a sliding brush autotransformer that furnishes a flat surface to aid in fabricating the winding contact surface over which the brush slides.

A further object is to provide a sliding brush autotransformer in which thermal insulation between the winding and core is reduced to the extent that the core becomes an efficient heat sink for the heat produced at the high temperature interface between the brush and winding.

Another object of the invention is to provide a heat sink for sliding brush autotransformers in which eddy current losses in the heat sink are minimized.

Another object of the invention is to improve adjustable autotransformers of the type having a winding coiled around an insulating form that often has an uneven surface by providing a heat sink that furnishes a flat, even surface for the winding to be wound on in spite of unevenness in the insulating form.

Other objects and advantages of the invention will become apparent from the drawing, specification, and claims, and the scope of the invention will be pointed out in the claims.

Briefly stated, according to one aspect of our invention, an adjustable autotransformer of the type having a substantially toroidal winding of successively disposed adjacent turns may have a circular electrical contact surface on the winding in a plane substantially perpendicular to the longitudinal centroidal axis of the winding. The winding contact surface provides a circular, commutator-like path for sliding electrical contact between a high resistance brush connectible to an external circuit and successive turns of the winding. Under many operating conditions sufficient heat is produced at the area of contact between the brush and winding contact surface to damage parts of the autotransformers. Our invention resides in the improvement that prevents damage from excessive heat at the area of contact between the brush and winding contact surface by the use of a substantially circular metal heat sink ring having its central axis substantially coincident with the longitudinal centroidal axis of the winding. The heat sink is substantially enveloped by the toroidal winding and has a flat, even outer surface located in a plane substantially parallel to the previously mentioned plane of the winding contact surface. The outer surface of the heat sink is in heat transfer relationship with the winding contact surface throughout the circular path of sliding movement of the brush. Thus effective distribution of heat into the heat sink and away from the area of contact is achieved for all positions of the brush along its circular path of movement.

In the drawing:

FIGURE 1 is an isometric, partially cross-sectional, schematic view of an adjustable sliding brush autotransformer in accord with the teachings of our invention.

FIGURE 2 is an enlarged, fragmentary, schematic cross-sectional view of the heat sink embodiment of FIGURE 1.

FIGURE 3 is an enlarged fragmentary, schematic cross-sectional view, corresponding to FIGURE 2, illustrating another embodiment of the invention.

FIGURE 4 is an enlarged, isometric, partially broken-away, schematic view illustrating still another embodiment of the invention.

FIGURE 5 is an isometric, partially cross-sectional, schematic view illustrating a further embodiment of the invention.

FIGURE 6 is an enlarged cross-sectional view taken generally along the line 6-6 in FIGURE 5.

FIGURE 7 is a cross-sectional fragmentary, schematic view on an exaggerated scale illustrating a deficiency of a prior art arrangement.

FIGURE 8 is a cross-sectional, fragmentary, schematic view on an exaggerated scale of the embodiment of FIGURES 1 and 2, illustrating an advantage of our invention when compared with the prior art arrangement of FIGURE 7.

Turning now to the drawings, and more particularly to

FIGURES 1 and 2, therein is illustrated an embodiment of an adjustable sliding brush autotransformer 10 in accord with the teachings of our invention. According to conventional practice, the autotransformer 10 has an annular core 11 of laminated form made by spirally winding a ribbon or sheet of magnetic iron or steel upon itself. The core 11 is enclosed in two generally U-shaped winding forms 12 made from insulating material, such as plastic. The forms may have serrations (not illustrated) in their outer edges to provide guides for placing and holding the insulated conductor forming the toroidal winding 13. The upper form 12 may have a thickened portion 14 at its outer circumference to ensure that the outer circumference of the winding 13 will be raised above the inner circumference of the winding; this ensures that insulation will be removed only from the raised portion of the winding when the commutator-like surface 15 is fabricated by methods described in paragraphs that follow.

20 The winding 13 is made from an insulated wire coiled about the core 11 to provide a plurality of successively disposed adjacent turns. An outer surface of the winding 13 is provided with commutator-like, electrical contact surface 15. The surface 15 lies in a plane substantially perpendicular to the longitudinal centroidal axis 23 of the winding, and provides a circular path for sliding electrical contact with a high resistance brush 16. The surface 15 may be formed by removing the insulation from the surface of the wire forming the winding 13 by 25 grinding the wire flat, so as to provide a relatively smooth surface for travel of the brush 16. An alternative arrangement is to provide on the previously ground flat contact surface, a layer of any of the well known materials usable for brush commutating surfaces. The materials 30 employed are usually high corrosion resistance, low electrical resistance metals or alloys. A more detailed disclosure of materials that have long been used in the art for this purpose may be found in standard textbooks, such as Electrical Contacts, by L. B. Hunt, published in 35 1946, by Johnson, Matthey & Co., Ltd.

The brush 16 is conventionally made from a high resistance carbon or graphite type material to prevent excessive currents when adjacent turns of the winding are short circuited. The brush may be mounted in a holder 40 17 secured to a radiator plate 18, which is mounted on a rotatable shaft 19 extending through the opening in the core. The brush 16 is urged against the surface 15 by a spring 20 so as to maintain a predetermined pressure therebetween. The shaft 19 may have a knob 21 attached thereto to facilitate manual turning of the shaft 19 to vary the position of the brush 16 on the surface 15. The radiator plate 18 aids in dissipating heat generated by the autotransformer particularly that generated in the brush. The core and winding assembly may 45 be supported on a base 22.

To operate the autotransformer 10, the ends of the winding 13 are connected to an external source E of alternating current, as for example, by plugging them in to an ordinary 120 volt outlet, as indicated schematically by the leads 24 and 25. The output terminals 26 and 27 of the autotransformer are connected respectively to the brush 16 and one of input leads 24, as indicated schematically in FIGURE 1. An external load 28 can be connected across the output terminals 26 and 27, and the 50 voltage and current received by the load are determined by the position of the brush 16 on the commutator-like contact surface 15 of the winding 13.

As is well known in the art, the heat generated at the interface between the brush 16 and the contact surface 15 is very great, making the area of contact by far the hottest spot in the autotransformer. This has resulted in autotransformers being insulated with the lowest type of electrical insulation acceptable for these purposes (Class A insulation), so that only a 55° C. rise of average winding temperature over ambient temperatures is provided

for. In prior art autotransformers the use of higher classes of insulation, which would enable the autotransformers to withstand higher temperature rises, and consequently greater loads for any given size, have not been used because the high temperature at the interface causes deterioration of the uninsulated surface 15, melting of the form 12, raising of winding turns under the brush, or burning out of the insulation on the winding 13 in the area adjacent the brush 16, before the electrical load on the apparatus causes failure of the insulation in other areas. The overall result is that prior art autotransformer winding and core assemblies have been operated at much lower load levels than they could be used for, if the high temperature at the interface were lowered.

To accomplish the above-described desirable result, autotransformers in accord with our teachings employ a substantially circular, ring-like, metal heat sink beneath the winding 13 in the area immediately adjacent the winding contact surface 15. The longitudinal centroidal axis of the heat sink should be substantially coincident with the longitudinal centroidal axis 23 of the autotransformer winding to ensure a symmetrical relationship. In the embodiments of FIGURES 1 and 2, the heat sink is a ring 30, which is made from a metal having a relatively high thermal conductivity and a relatively low electrical resistance. The ring 30 should be at least as wide as the brush 16. It has been found that silver, copper, and aluminum possess desirable properties in the above given order of preference. Other metals having lower thermal conductivity also may be employed. Alloys of the above mentioned metals are usable as the heat sink material, and in particular brass and bronze are highly suitable. It is also possible to employ a metal plated with a different metal, as for example, brass plated with silver will provide the high conductivity of silver on its exterior surface without the expense of a ring of solid silver. A very thin layer of electrical insulation should be placed between the winding 13 and the heat sink 30. For example, when the heat sink 30 is made from aluminum, it has been found that an anodized coating several mils thick provides satisfactory electrical insulation.

The use of a substantially circular, ring-like heat sink, such as 30, provides the additional advantage that heat will be conducted substantially equally in both directions away from the high temperature interface between the brush 16 winding contact surface 15 regardless of the location of the brush along its path of movement. The reason is that because the ring is continuous and circular, there will be a continuous metal path on both sides of the brush to conduct heat in both directions circumferentially around the ring no matter where the brush is located.

Another advantage of a heat sink arrangement in accord with our teachings is that the heat sink cannot act as a short-circuited turn about the flux in the core. In prior art heat sink arrangements, complicated and expensive constructions had to be employed in order to prevent the heat sink from becoming a short-circuited turn about the flux in the core, since this would have caused the heat sink to burn up in a very short time. In our arrangement the outer surfaces of the heat sink define a closed metal polygon in a plane that is parallel to the cross-sectional plane of the core through which the flux travels; this construction provides a large mass of metal for absorbing heat. However, the closed metal polygon does not go around the core, and thus cannot be a short-circuited turn. This relationship is illustrated in FIGURE 1 wherein the cross-sectional plane of the core through which the flux travels, and the plane in which the outer surfaces of the heat sink define a closed metal polygon are both the plane in which the core 11 and heat sink 30 are shown in cross section. The last-mentioned plane is substantially perpendicular to the plane of the contact surface 15 in which the brush 16 makes electrical contact with the winding 13.

There is bound to be some eddy current loss in the heat sink because of the stray flux from the windings and core. However, the metal surface area in the above-mentioned cross sectional plane of the heat sink, in which the eddy currents are generated, is relatively small. Consequently the eddy current losses in the heat sink are kept at a low level. Furthermore, autotransformers employing our improved arrangement can be operated at much higher temperatures than those constructed according to the prior art. This reduces eddy current losses even further, since the resistance of the heat sink goes up as its temperature rises.

In the embodiment of FIGURE 3, the structure of the autotransformer is identical to that shown and described with reference to FIGURES 1 and 2, except that the heat sink 35 is a laminated structure. The heat sink 35 can be formed by winding a length or strip of high conductivity metal about itself to form a spiral, or it can be made by placing a plurality of circular rings concentrically about each other. This type of structure reduces eddy current losses because eddy currents can only be formed in each individual lamination 36 and not in the entire cross sectional area of the heat sink.

FIGURE 4 illustrates another embodiment of the invention in which the autotransformer is identical to that disclosed with reference to FIGURES 1 and 2, except for the structure of the heat sink 40. The heat sink 40 has integral therewith a plurality of projections 41 that extend through the insulating form member 12 into contact with the core 11. This arrangement provides a metal path between the winding contact surface 15 and the core 11 through which heat can be conducted to the core that is broken only by the thin layer of insulation between the winding 13 and heat sink 40. Since the core is at a lower temperature than the winding-brush interface, it acts as a mass of metal providing an additional heat sink mass for carrying heat away from the interface. The embodiment of FIGURE 4 can be manufactured by drilling holes in the form member 12 for the projections 41 to extend through, or the form member 12 can be cast around the heat sink 40.

FIGURES 5 and 6 illustrate another embodiment of the invention in which the core itself serves as the heat sink. In this embodiment, the core 50 is formed by winding a tapered strip of core material in spiral fashion about itself. The radially inner end 51 of the strip is smaller than the outer end 52 and gradually increases in width until a predetermined point 53 is reached, after which the strip is of continuous width. This arrangement provides a flat even upper surface 54 on the core 50 on which the winding contact surface 15 can be fabricated. Only a predetermined minimum amount of electrical insulation 55 is provided between the winding 13 and the upper surface 54 of the core, so as to prevent electrical breakdown but permit good heat transfer therebetween. For example, where the electrical stresses encountered are up to about 1500 volts, a coating of plastic insulation such as an epoxy resin about 5 mils thick provides satisfactory electrical insulation; the thin coating also permits relatively good heat transfer between the surface 15 and the core 50.

Experiments have shown that when our heat sink arrangement is employed, the high temperatures at the winding-brush interface do not cause destruction of the surface 15 or insulation in the area of contact before the winding insulation fails in other areas. In the experiments, autotransformers with and without aluminum heat sinks of the type shown in FIGURES 1 and 2 were run at overload currents of more than twice their rated load capacity until failure occurred. In those autotransformers having a heat sink, the failures occurred in the winding insulation, with no failures occurring at the area of contact between the brush and winding. In those autotransformers without heat sinks, the failure occurred in the area of contact before the winding insulation failed.

These experiments are believed to prove that by employing a heat sink in accord with our teachings, the high temperatures at the interface between the brush and winding contact surface will not be the limiting factor in the construction and operation of the autotransformers. Instead, the electrical insulation in other parts of the apparatus is the limiting factor, and the load capacity of the autotransformer can be increased by utilizing higher classes of insulation. This was not practical in prior art devices.

During construction of commercial embodiments of sliding brush autotransformers employing heat sinks of the structure shown in FIGURES 1 and 2, an unexpectedly beneficial result was discovered which eliminated a problem encountered in another area. This can be explained by reference to FIGURES 7 and 8. FIGURE 7 illustrates a problem encountered in making prior art autotransformers in which no heat sink is employed, beneath the winding 13. In fabricating the autotransformer, the wire 59 forming the winding 13 was coiled around the core 11 after the insulating form 12 had been placed thereon. After this was done, an abrasive wheel 60 was employed to remove insulation from the winding and to grind flat the upper surface of adjacent turns to produce the winding contact surface 15. The dotted line 61 illustrates what the orientation of the surface 15 would be, if the upper surface of the thickened portion 14 which supports the wire 59, were truly flat. However, it has been found that a high percentage of the form 12 slant or droop slightly at the outer circumference of the thickened portion 14 so that they provide a supporting surface on which the wire 53 is wound that slants, as indicated by the dotted line 62. The result is that when the slanting surface on the portion 14 is cut by the abrasive wheel 60, the wire 59 is cut more deeply at its circumferentially inner end 64 than at its outer end 65. This reduces the cross-sectional area of the wire more than necessary, which greatly increases its resistance and reduces its mechanical strength. The result is that the winding will frequently burn out at a relatively low load level, or in some cases, the abrasive wheel will completely cut through the wire. The same problem occurs when the inner end of the form 12 slants below the outer end, except that in this case the outer end 65 of the wire 59 is cut more deeply than its inner end 64.

Turning now to FIGURE 8, the arrangement of parts is the same as in FIGURE 7 except that the form 12 has a groove 66 therein for receiving the heat sink 30. The circumferentially outer end of the form 12 may droop or slant slightly, so that it deviates from a truly flat surface by the difference between the lines 61 and 62, as in the prior art arrangement of FIGURE 7. However, regardless of the amount of droop or unevenness in the upper surface of the thickened portion 14, the ring-like heat sink 30 will seat itself in the groove 66 as soon as one corner, such as 67, touches part of the groove. The circular ring-like structure employed is very stiff, and consequently the heat sink 30 will not be deformed so as to conform to the contour of the groove 66. Therefore, the wire 59 will be wound over the flat even surface 68 on the top of the heat sink in a plane substantially perpendicular to the longitudinal centroidal axis of the winding. When the abrasive wheel 60 removes insulation and flattens adjacent turns, it will cut evenly through the wire 59 and will not produce portions with greatly reduced cross-sectional areas as is the prior art arrangement in FIGURE 7. Thus, by practicing our invention an unexpected result was achieved in an area not related to heat transfer, and a problem encountered in prior art embodiments was solved.

It has thus been shown that by the practice of our invention, the high temperature generated at the interface between the brush and commutator-like contact surface of the winding has been eliminated as the critical feature in constructing and operating adjustable sliding brush

autotransformers. The high temperatures previously encountered are greatly reduced because an effective heat sink is provided for carrying heat away from interface. This permits the use of higher classes of insulation, which in turn permits an operating temperature rise of higher magnitude for the autotransformer. The result is that for any given size of core and winding assembly, the autotransformer can be operated at greater loads than were previously possible for the given size.

It will be understood, of course, that while the forms of the invention herein shown and described constitute preferred embodiments of the invention, it is not intended herein to illustrate all of the equivalent forms or ramifications thereof. For example, those skilled in the art will realize that our invention is also applicable to those embodiments of sliding brush autotransformers wherein the brush slides along an electrical contact surface on the side of the winding, in contrast to the illustrated embodiments where the contact surface is on the top of the winding. It will also be understood that the words used are words of description rather than of limitation, and that various changes may be made without departing from the spirit or scope of the invention herein disclosed, and it is aimed in the appended claims to cover all such changes as fall within the true spirit and scope of the invention.

What we claim as new and desire to secure by Letters Patent of the United States is:

1. In an adjustable transformer of the type having a substantially toroidal winding of successively disposed adjacent turns of wire, said winding having on the exterior thereof a circular electrical contact surface that provides a circular path for sliding electrical contact between a high resistance brush connectable to an external circuit and successive turns of said toroidal winding, and sufficient heat being produced at the area of contact between said brush and contact surface to damage parts of said transformer, the improvement that prevents damage from excessive heat at said area of contact comprising a closed continuous substantially circular ring-like metal heat sink having its central axis substantially coincident with the central axis of said toroidal winding, the axial thickness of the heat sink ring being at least several times the thickness of said wire, said heat sink being enveloped by said toroidal winding and having a flat even outer surface in heat transfer relationship with said contact surface and closely adjacent the inner surface of the winding opposite to said contact surface throughout the circular path of sliding movement of said brush, whereby heat produced at any area where said brush contacts said contact surface will be substantially equally distributed throughout said heat sink in opposite directions away from the area of contact for all positions of said brush along its circular path of movement.

2. In an adjustable autotransformer of the type having a substantially toroidal winding of successively disposed adjacent wire turns having thereon a circular electrical contact surface in a plane substantially perpendicular to the longitudinal centroidal axis of said winding, said contact surface providing a circular path for a sliding electrical contact between a high resistance brush connectable to an external load circuit and successive turns of said winding, and sufficient heat being produced at the area of contact between said brush and contact surface to damage parts of said autotransformer, the improvement that prevents damage from excessive heat at said area of contact comprising a closed substantially circular metal heat sink ring having its central axis substantially coincident with said longitudinal centroidal axis of said toroidal winding, the axial thickness of the heat sink ring being at least several times the thickness of said wire, said heat sink being substantially enveloped by said toroidal winding and having a flat even outer surface located in a plane substantially parallel to said

plane of said contact surface in heat transfer relationship with said contact surface and closely adjacent the inner surface of the winding opposite to said contact surface throughout the circular path of sliding movement of said brush, whereby heat produced at any area where said brush contacts said contact surface will be effectively distributed throughout said heat sink away from the area of contact for all positions of said brush along its circular path of movement.

3. The invention defined in claim 2 in which said heat sink is made from a metal having relatively high thermal conductivity, and relatively low electrical resistance.

4. The invention defined in claim 2 in which said heat sink is made from a metal selected from the group consisting of copper, aluminum, silver, and alloys thereof.

5. The invention defined in claim 2 in which said heat sink is made from a strip of metal convolutely wound to provide a plurality of contiguous laminations that minimize eddy current losses in the heat sink, the plane of the turns of said heat sink being perpendicular to the plane of the turns of said winding.

6. The invention defined in claim 2 in which said toroidal winding substantially envelops an annular core made from magnetic metal, said heat sink and core being separated by a layer of non-metallic electrical insulating material that also thermally insulates the core from the heat sink, and said heat sink having metal projections extending through said insulating material at a plurality of locations into contact with said core so as to provide an essentially unbroken metal path for conducting heat from said area of contact to said core.

7. In an adjustable autotransformer of the type having a substantially toroidal winding of successively disposed adjacent turns of wire substantially enveloping an annular core, said toroidal winding having thereon a circular electrical contact surface in a first plane substantially perpendicular to the longitudinal centroidal axis of said toroidal winding, said contact surface providing a circular path for sliding electrical contact between a high resistance brush connectible to an external load circuit and successive turns of said toroidal winding, sufficient heat being produced at the area of contact between said brush and contact surface to damage parts of said autotransformer during operation of said autotransformer, said toroidal winding producing magnetic flux traveling through said core in a substantially circular path on the inside of the toroid, and essentially all of the flux in said toroid passing through a second plane substantially perpendicular to said first plane, the improvement that prevents damage from excessive heat at said area of contact comprising a continuous heat sink ring between said core and toroidal winding made of metal having relatively high thermal conductivity and relatively low electrical resistance, said heat sink having its central axis substantially coincident with said longitudinal centroidal axis, the axial thickness of the heat sink ring being at least several times the thickness of said wire, said heat sink defining a flat even substantially circular ring-like metal surface located in a third plane substantially parallel to said first plane, said metal surface being in heat transfer relationship with said contact surface throughout the circular path of sliding movement of said brush, whereby heat produced at any area where said brush contacts said contact surface will be effectively distributed throughout said heat sink away from the area of contact for all positions of said brush along its circular path of movement, and the outer surface of said heat sink defining a closed metal polygon in a fourth plane substantially parallel to said second plane, said closed metal polygon being outside the path of the flux in said core.

8. An adjustable sliding brush autotransformer comprising a substantially toroidal winding of successively disposed adjacent wire turns having thereon a circular electrical contact surface in a plane substantially per-

10

pendicular to the longitudinal centroidal axis of said winding, said contact surface providing a circular path for sliding electrical contact between a high resistance brush and successive turns of said windings, an annular core of magnetic metal substantially enveloped by said winding, a shaft extending through a hole in the center of said core, said shaft being rotatably mounted in a base supporting the core and winding assembly, a metal radiator plate being attached to said shaft so as to be rotatable therewith, said brush being supported by said radiator plate and rotatable therewith along said circular path, a closed substantially circular heat sink ring made of metal of relatively high thermal conductivity and relatively low electrical resistance, said heat sink having its central axis substantially coincident with said longitudinal centroidal axis of said winding and being enveloped by said toroidal winding, the axial thickness of the heat sink ring being at least several times the thickness of said wire, said heat sink providing a flat even outer surface located in a plane substantially parallel to said plane of said contact surface in heat transfer relationship with said contact surface and closely adjacent the inner surface of the winding opposite said contact surface throughout the circular path of sliding movement of said brush, whereby heat produced at any area where said brush contacts said contact surface will be effectively distributed throughout said heat sink away from the area of contact for all positions of said brush along its circular path of movement.

9. In an adjustable sliding brush transformer, a toroidal magnetic core, a circular insulating end cap over an end of said core, said cap having an outwardly open circular channel in its outer periphery, a closed continuous metal ring having a flat outer surface fitted into said channel, a toroidal coil of insulated wire electromagnetically linking said core and wound spirally over said end cap and metal ring, the outer portions of the turns of said wire where they overlie said metal ring having their insulation removed so as to constitute a circular brush track, the flat surface of said ring underlying said circular brush track constituting a planar support for said circular brush track, and an electrical brush wide enough to bridge across at least two adjacent turns of said wire and movable along said brush track, said metal ring additionally constituting a symmetrical heat sink for conducting localized heat developed by the action of said brush in bridging adjacent turns away from the brush area equally in circumferentially opposite directions for all positions of said brush on said brush track, said metal ring having a thickness several times the thickness of said wire.

10. In an adjustable sliding brush transformer, a toroidal laminated magnetic core of convolutely flatwise wound magnetic strip material, a pair of mating electrical insulating material circular end caps of rectangular channel shaped cross section fitting axially over and enclosing said core, one of said caps having a circular web portion with an outwardly open circular groove in its outer periphery, a flat outer surfaced nonmagnetic continuous metal ring fitted into said groove, a toroidal coil of insulated wire electromagnetically linking said core and wound spirally over said plastic end caps and metal ring, the outer portions of the turns of said wire where they overlie said metal ring having their insulation removed so as to constitute a circular brush track, the flat outer surface of said ring underlying said circular brush track constituting a planar support for said circular brush track, and an electrical brush wide enough to bridge across at least two adjacent turns of said wire and movable along said brush track, said metal ring additionally constituting a symmetrical heat sink for conducting localized heat developed by the action of said brush in bridging adjacent turns away from the brush area equally in opposite directions for all positions of

said brush on said brush track, said metal ring having a thickness several times the thickness of said wire.

11. In an adjustable sliding brush transformer, a rectangular cross section toroidal magnetic core of convolutely flatwise wound uniform width magnetic strip material, a pair of mating molded plastic circular end caps of rectangular channel shaped cross section fitting axially over and enclosing said core, one of said caps having a circular web portion with an outwardly open circular channel in its outer periphery of rectangular cross section, a rectangular cross section flat surfaced closed metal ring fitted into said channel, a toroidal coil of insulated wire electromagnetically linking said core and wound spirally over said plastic end caps and metal ring, the outer portions of the turns of said wire where they overlie said metal ring having their insulation removed so as to constitute a circular brush track, the flat surface of said ring underlying said circular brush track constituting a planar support for said circular brush track, and an electrical brush wide enough to bridge across at least two adjacent turns of said wire and movable along said brush track, said metal ring additionally constituting a symmetrical heat sink for conducting localized heat developed by the action of said brush in bridging adjacent turns away from the brush area equally in circumferentially opposite directions for all positions of said brush on said brush track, said metal ring having a thickness several times the thickness of said wire and being laminated in a direction perpendicular to the direction of magnetic flux therein produced by said coil.

12. In an adjustable sliding brush transformer, a rectangular cross section toroidal main magnetic core of convolutely flatwise wound uniform width magnetic strip material, a pair of mating molded plastic circular end caps of rectangular channel shaped cross section fitting
